United States Patent Office

Des. 178,994
Patented Oct. 23, 1956

178,994

DOOR STOP OR SIMILAR ARTICLE

Wilbur W. Gislason, Cleveland, Ohio

Application August 15, 1955, Serial No. 37,448

Term of patent 14 years

(Cl. D10—7)

Fig. 1

Fig. 2

Fig. 3

Fig. 4

In the drawing Fig. 1 is a top plan view of a door stop embodying my new design;

Fig. 2 is a side elevation thereof;

Fig. 3 is a right end view of the door stop; and,

Fig. 4 is a bottom view of the door stop as shown in Fig. 2.

I claim:

The ornamental design for a door stop or similar article, as shown.
